CARTON FOR CUSHIONED SHIPPING AND
DISPLAYING FRAGILE ARTICLES

Irving I. Klener, Brooklyn, N. Y.

Application September 5, 1947, Serial No. 772,296

13 Claims. (Cl. 229—27)

1

This invention relates to shipping cartons for packaging fragile articles such as those made wholly or partly of glass, and more particularly is directed to an improvement of a carton which is constructed to support fragile articles therein cushioned to absorb shocks and strains in transportation and when roughly handled.

Among the objects of the invention is to provide a carton for cushioned shipping and displaying fragile articles of the character described comprising few and simple parts, which shall be readily assembled from a single blank sheet material such as corrugated paper board to form a carton container or receptacle of inexpensive construction having integral cushioning means for supporting a fragile article within the carton against damaging from rough handling in shipping and storage, which shall form a display means of neat and attractive appearance for an article packed therein when partly open, and which shall be practical and efficient to a high degree in use.

Other objects of the invention will in part be obvious and in part hereinafter pointed out.

The invention accordingly consists of the features of construction, combination of elements and arrangement of parts which will be exemplified in the construction hereinafter described, and of which the scope of the application will be indicated in the following claims.

In the accompanying drawing in which is shown one illustrative embodiment of this invention:

Fig. 1 is a plan view of a flat sheet of corrugated paper board in the form of a rectangular shaped blank with fold or score lines and partially through cut lines laid out to provide a collapsible improved carton embodying the invention for cushioned shipping and display of fragile articles.

Fig. 2 is a plan view like Fig. 1 showing corner portions of the blank folded into positions for forming integral cushioning and display structures in assembling the improved carton.

Fig. 3 is a fragmentary cross-sectional view taken on line 3—3 in Fig. 2.

Fig. 4 is a plan view like Fig. 3 showing the integral cushioned structures infolded and secured together with the front, back and top panel sides of the carton in an unfolded flattened-out position.

Fig. 5 is a sectional view taken on lines 5—5 in Fig. 4.

Figs. 6, 7 and 8 are plan views of detached portions of the blank shown in Fig. 1 which form

2

various members used in the improved carton construction.

Fig. 9 is a cross-sectional view taken midway through the improved carton assembled to serve as a cushioned shipping and display container for a glass or mirror panelled cosmetic vanity case shown packed therein.

Fig. 10 is a top elevational view corresponding to the assembly shown in Fig. 9 showing the top panel side of the carton cut away to expose the interior construction with details of the top and side cushioning supporting arrangement surrounding said enclosed vanity case, and

Fig. 11 is an enlarged cross sectional view showing alternative means for safely packing the mirror in the carton when dismounted from the vanity case using member portion of blank shown in Figs. 1 and 6 as a cushioning spacer interposed between the mirror and the vanity case.

20 Referring now to the drawing. In Fig. 1, a blank 20 may be cut and scored from suitable sheet material such as corrugated paper board of any well known manufacture used for making shipping cartons and containers. In practicing the invention for economy and to avoid waste, the blank 20 is cut rectangular in shape and is so constructed and arranged that substantially each and every part thereof is utilized in forming the finished carton for cushion shipping and displaying fragile articles, such for example as mirror or glass panelled cosmetic vanity case V shown in Figs. 9 and 10.

The blank 20 when cut from a single sheet or from a web forming a roll of corrugated paper board of suitable width, is seen to comprise the following successive wall sections or panels extending through the center portion thereof, a rear wall 21 adapted to provide an inner panel which is separated from a rear wall 22 forming an outer panel by spaced fold or score lines 23. A bottom center section 24 is separated from said rear outer wall 22 by fold or score line 25 and adjoins an outer front wall panel 26 separated from said bottom section 24 by fold or score line 27. A top section 28 adjoins said front section 26 and is separated therefrom by the fold or score line 29. Said top section 28 may be formed with integral side flaps 28a on opposite sides which are separated from said top section 28 by spaced fold or score lines 30 extending at right angles, that is, transverse the fold or score line 29. Extending as a continuation of each of said score lines 30 there is provided a partial through-cut 31 which forms opposite edges of outer front wall panel 26. Each of said cuts 31 also extends to the score lines

30 of flaps 28a which are preferably made slightly shorter than the actual width of the top section 28 as shown in Figs. 1 and 2 so as to fit in the effective assembly structure as clearly shown in Figs. 9 and 10.

Each of the partial through-cut lines 31 connects with a fold or score line 32 which form opposite edges of bottom section 24, and connecting with the score lines 32 are spaced apart partial through-cuts 33, the latter forming successively opposite edges of said outer and inner rear wall sections 22 and 21, respectively.

Except for two space sections 34 that extend outwardly from bottom section 24, which form end panels for the carton and are separate from the said bottom section 24 by score lines 32, the remaining portions of blank 20 as yet not described, provide material for making up the interior cushioning structure for the improved carton, there being spaced apart fold or score lines 25a and 27a, which are continuations of score lines 25 and 27, respectively, and which with score lines 32 bound said section end panels 34.

Each partial through-cut line 33 with parallelly aligned partial through-cut lines 35 and 36 spaced therefrom provided in the blank 20 beyond said inner and outer rear wall panels 21 and 22, form a pair of bottom side cushions spacer portions 37 and a pair of end panel cushioning integral members 38 located above, that is, outwardly 30 of said spacer portions 37. A pair of cross-bracing portions 39 and 40 are also provided beyond each of the cushioning members 38 as seen in Figs. 1, 4 and 5.

The bottom side cushion spacer portions 37 because of being proportioned to extend along a greater part of the width of both the inner and outer wall sections 21 and 22 are sufficient to form looped structures in the set up assembly, said portions 37 may be provided with central extension tabs 37a that can be secured together in overlapped relation by suitable fastening means, such as a staple 41, shown in Figs. 4 and 5. In order to permit forming said cushion spacer portion 37 into a looped structure, spaced transversely extending fold or score lines 42 are provided at opposite ends thereof and a fold line 37b on each of the tabs 37a facilitates positioning the latter for fastening by staple 41 as can be seen from Figs. 1 and 4.

The pair of end panel cushioning integral members 38 are each formed into effective position by providing, beside each fold or score line 42, another fold line 43 between line 42 and one end edge 20a of the blank 20, two closely spaced short fold lines 44 extending outwardly beyond each tab 37a, a pair of spaced fold lines 45, and a two fold line 46 spaced similarly to lines 44 between lines 45 and adjacent fold lines 42. All of said fold lines 42, 43, 44 and 45 are parallelly aligned, and an L-shaped slit 46a may be extended along one of said fold lines 46 and across to the other for purposes hereinafter described.

As seen from Figs. 1, 3 and 4, each of said cushioning members 38 is folded on score lines 65 aforementioned to stand against the interior side of end panel 34, and is braced by an intermediate triangular shaped structure T formed on fold lines 44, 45 and 46, as shown in Figs. 3 and 4. To retain the said triangular shaped bracing structures T rigid, coupling sections 50 and 51, each formed with slots 50a and 51a, respectively, may be used to interlock with slits 46a and the cut out portion of members 38 left by tabs 37a. Said coupling sections 50 and 51 are shown as a

10

corner portion of the blank 20 in Fig. 1, and detached in Figs. 7 and 8, respectively. In Figs. 2, 3, 4, and 5, coupling section 50 and 51 are shown in effective interlockment with the triangular bracing structure T.

Cross bracing portions 39 and 40 which border on opposite longitudinal edges 20d and 20c of blank 20, respectively, are adapted to hinge on fold lines 25a, said portions 39 and 40 terminating in suitable interconnectable ends, as for example, a male terminal 39a and a cooperative slot 40a, respectively, as shown in effective position in Fig. 4.

The improved carton construction above described provides for bottom and end cushioning means up to the cross bracing portions 39 and 40. Since, for the purposes described, it is often desirable to provide additional cushioning means in the region of the top of the carton, such may be provided as an integral part of blank 20 with a minimum of waste. To this end there is provided between the top section flaps 28a and the edges 20b and 20c of the blank 20, symmetrically disposed partial through-cuts 48 which provide a pair of front cushioning members 49 adapted in the set up assembly to be positioned for cooperating with end cushioning members 38 and top side cushioning spacers 52 which are above, that is, outwardly of said members 49.

Cushioning members 49 each have spaced fold or score lines 53 extending from flaps 28a to the cut line 48, and a pair of similarly spaced fold lines 54a and 54b parallelly aligned therewith but extending from cut line 31 to each of the blank edges 20d and 20c. An L-shaped through-cut 55 in each cushion spacer 52 may be provided to connect with said cut 48 to form a tongue 56 spaced fold or score lines 57 being provided for bending said tongue 56 out of the normal plane of spacer 52 into an effective position as shown in Fig. 10. Said tongue 56 can be slotted as at 56a to increase the flexibility of the end thereof.

As seen from Figs. 1, 2, 3, and 4 the remaining symmetrically positioned sections 60 of the blank 20 bound by score lines 27a, 54a, cut line 31 and portions of blank edges 20c and 20d provide inner front wall panels in the set up carton as shown in Fig. 10.

Where said vanity case V to be packed has 50 protruding ornamentations or draw handles H, suitable cushioning clearancing means may be provided in the cushioning structures, such as formed by providing spaced through-cuts 58 with fold or score lines 59 in members 49 shown in Fig. 1 as extending transversely fold lines 54a and 54b and as shown effective to clear handle H of the vanity case V in Figs. 9 and 10.

The practical application of the invention will now be apparent. After providing the rectangular shaped corrugated paper board blank 20 formed with all the fold or score lines and through cut lines, some of the latter being only partially cut through so as to retain all portions against accidental detachment as described above and shown in Fig. 1, said blanks 20 are then in most compact shape and size for stacking in storage and shipment before setting up as cartons.

Each blank 20 may be set up as a carton by first detaching members 50 and 51, and a member 61 which forms the corner of blank 20 opposite said members 50 and 51, adjacent cross member 40.

Next, the remaining portions of the blank 20 on either side of inner and outer rear walls 21 and 22 are folded on score lines 25a to overlie

end section panels 34, that is, folded from the position shown in Fig. 1 to that shown in Fig. 2. Also the portions of the blank 20 on either side of the through-cuts 31 and side flaps 28a of top section 28 are folded over score lines 54a to overlie inner front wall panels 60.

Member 37 is then looped to extend over bottom section 24, member 38 folded on score lines 42, 43, 44, 45 and 46, to provide said construction T, and member 49 folded on score lines 54a, 54b and 53 as shown in Figs. 3 and 4. The free end portion of said members 38 and 49 may then be secured in place to end panels 34 by suitable fastening means, such as staples 62, and coupling section 50 and 51 inserted to retain the said formations T.

The end panels 34 may next be folded from the position shown in Fig. 2 to that shown in Fig. 4, that is, on score lines 32 to upstand from the bottom section 24, and cross bracing 39 and 40 interlocked. Tabs 37a of spacer portion 37 may be folded over on score lines 37b and secured in position by a staple 41 for making the set up structure sufficiently rigid for seating the vanity case V in proper position on edgewise positioned bottom spacer 37 between end cushioning members 38 and against interlocked cross bracing member 39 and 40.

The inner and outer rear panels 21 and 22 may then be folded on score lines 23 and 25 so as to form a double upright rear wall cushioning structure with the interlocked cross braces 39 and 40 extending therebetween, the wall section 21 being slotted at 63 on a sufficient spaced apart portion from the end thereof as shown in Figs. 1 and 4 to clear the thickness of the end cushion members 38, as shown in Fig. 10.

With the front section 26 and top section 28 still in flattened out position, the front and top vanity case V is exposed and the carton in this condition may serve as a display receptacle. Now to complete packing the vanity case V, inner panels 60 are folded on score lines 27a to bring cushion supports formed by members 49 against the front side of the vanity case V and top cushioning spacer 52 may be folded on score line 54a and 54b and the tongue 56 folded on score lines 57 so as to bear against portions of the glass top side of the vanity case V, which may be hinged covers of compartments. The tongue 56 will take care of differences in height of said vanity case top side as clearly shown in Figs. 9 and 10.

If a trunnioned mirror M forms part of the vanity case V as shown in Figs. 9 and 10, the tongues 56 serve to retain the mirror against swinging displacement for the packed position.

Where the vanity case V is provided with protruding drawer handles H, or other ornamentation, the portion of member 49 bound by cut lines 58 and score line 59 may be utilized for clearances as shown in Figs. 9 and 10.

With the top section 28 down-folded on score line 29 and flaps 28a in-folded on score lines 30, a firm relative tight closure is provided which may be sealed in any well understood manner, as for example with adhesive tape, not shown.

It should be noted that the improved carton with the vanity case V packed therein is supported in spaced relation from the top and bottom wall sections 28 and 24, respectively, by edgewise position spacers 49, 52 and 37, respectively, which retain said vanity case V against damage and absorb jarring effects to which the carton may be subjected from the top and bottom sides thereof, while the front and rear up-

right sections 60, 26, and 21, 22 provide spaced double wall constructions to form effective abutment cushioning means at the front and rear sides of the carton, and end sections 34 with member 38 forming a spaced double walled cushioning construction for the opposite ends of the vanity case V thus completely guarding the latter from direct impact strains and stresses to which the upright sides of the vanity case V may be subjected.

10 The above described cushioning structures formed by the interior and exterior of the carton as described above and shown in the drawing also have been found to protect the packed vanity case V against injury that may be caused by accidental dropping of packed carton on a corner thereof since said cushioning structures served as a bracing construction of sufficient resiliency so constructed and arranged to absorb such impacts without damaging the fragile contents.

15 As an alternative means for safely packing the mirror M in the carton when dismounted from the vanity case V, there may be provided an arcuate slit 64 formed with a finger hole 64a to extend along inner rear wall sections 21 inwardly of end edge 28a of blank 20, said slit 64 may be used with member 61 having spaced tongues 61a for packing the mirror M against said inner wall sections 21 with said member 61 as a cushioning spacer interposed between the mirror M and the rear of the vanity case V as shown in Fig. 11.

20 Where the carton is to be used for package shipping of straight sided fragile articles only and the display feature not desired, the above described construction of the carton may be simplified by substituting in portions of the blank 20 in place of cross bracing portions 39, 40, coupling sections 50, 51 and member 61, a duplication of top spacer portions 52 with tongue 56 as additional cushioning means as has already been described and shown. In this latter construction it is desirable to apply adhesive tapes in the well understood manner to the upright edges of the carton for retaining the outer rear wall section 22 to the upstanding end panels 34.

25 It is thus seen that there is provided a construction whereby the several objects of the invention are achieved, and which is well adapted to meet the conditions of practical use.

30 As various possible embodiments of the above invention might be made, and as various changes might be made in the embodiment above described, and shown in the drawings, it is to be understood that all matters herein set forth or shown are to be interpreted as illustrated and not in a limiting sense.

35 Having thus described my invention, I claim as new and desire to secure by Letters Patent:

1. A carton for cushioned shipping and displaying fragile articles of the character described formed of a single blank of sheet material comprising successive centrally extending sections foldably interconnected to provide a double spaced apart inner and outer rear wall, bottom, front outer wall and a top wall for the carton, spaced end wall sections foldably interconnected to extend from said bottom sections, spaced apart bottom spacer portions and end cushioning members foldably interconnected to extend from said end wall sections, said blank having through-cuts separating said bottom spacer portions from said inner and outer rear wall sections and dividing each of said bottom spacer portions from the end cushioning members, an inner front wall section and spaced apart top spacer por-

tions foldably interconnected to extend from each of said end wall sections oppositely disposed to said bottom spacer portions and end cushioning member, a front wall cushioning member foldably interconnected to extend from each of said inner front wall sections, said blank having other through-cuts separating each inner front wall section from the outer front wall section, and dividing each front wall cushioning member from the said top wall section and top spacer portions from said front wall cushioning member.

2. The carton as defined in claim 1 in which said blank is rectangular in shape and includes detachable sections adapted to cooperate with the interior cushioning structure of the carton.

3. The carton as defined in claim 1 in which said blank is rectangular in shape and includes detachable sections adapted to cooperate with the interior cushioning structure of the carton, and interlockable cross bracing portion foldably interconnected to extend from said end sections.

4. In a blank for forming a carton of the character described, cushioning wall formation means comprising bottom and spaced end wall sections foldably interconnected, sections foldably interconnected together and to said bottom wall section for extending to provide a double spaced apart inner and outer panelled rear wall, and bottom spacer portions foldably interconnected to said end wall section, said blank having through-cuts separating said bottom spacer portions from said inner and outer panelled rear wall, an interconnection portion extending from each of the bottom spacer portions bendably constructed for looping thereof into an effective position on the bottom wall section.

5. In the blank for forming a carton of the character described as defined in claim 4 including attachment means extending from each bottom spacer portion so constructed and arranged to secure said spacer portions together in an effective cushioning position on the bottom wall section.

6. In the blank for forming a carton of the character described as defined in claim 4, including end cushioning members foldably extending from said end wall sections, said through-cuts separating the bottom spacer portions from said inner and outer panelled rear wall.

7. In the blank for forming a carton of the character described as defined in claim 4, including end cushioning members foldable from said end wall sections, said through-cuts separating the bottom spacer portions from said inner and outer panelled rear wall, each of said spacer portions having a foldable inter-connected tab extension to secure said spacer portions together in an effective cushioning position on the bottom wall section when said carton is set up to receive an article to be packed therein.

8. In a blank for forming a carton cushioning wall formation means comprising successive extending sections foldably interconnected to provide bottom, outer front panel and a top wall for the carton, spaced end wall sections foldably interconnected to extend from said bottom section, and inner front panel wall and top spacer portion foldably interconnected to extend from each of said end wall sections, a front wall cushioning member foldably interconnected to extend from each of said inner front panel wall sections, said wall formation means having through-cuts separating each inner front panel wall sections from the outer front wall panel

section and dividing each front wall cushioning member from the said top panel wall section and a top spacer portion, and foldable interconnections for each top spacer portion to permit positioning thereof as edgewise shock absorbing means between the top wall section and the carton contents.

5 9. In a blank for forming a carton cushioning wall formation means as defined in claim 8, in which said through-cuts provide tongues in each of said top spacer portions, and a clearance portion in each of said front wall cushioning members, and foldable interconnections for said tongues and clearance portions to permit effective 10 15 positioning thereof in said cushioning wall formation.

10 10. A carton for cushioned shipping and displaying fragile articles of the character described 20 formed of a single blank of sheet material having score lines and through-cuts, said blank being folded on said score lines into interconnected sections 25 separate from each other by said through-cuts to provide a top and a bottom wall with edgewise positioned spacers positioned between each of said top and bottom walls and the top and bottom side, respectively, of a fragile article packed in said carton, spaced double wall constructions forming abutment cushioning means for the front and rear of said article to 30 serve as the front and rear sides of the carton, end panels each having an interior cushioning member for opposite ends of said article for completely cushioning and resiliently protecting said article to absorb impacts on any exterior part 35 of the carton, and interlocking cross bracing portions foldably interconnected with said end panel sections extending between the double wall construction to form an abutment cushioning means at the rear of said article.

40 11. A carton for cushioned shipping and displaying fragile articles of the character described 45 formed of a single blank of sheet material having score lines and through-cuts, said blank being folded on said score lines interconnected sections 50 separate from each other by said through-cuts to provide a top and bottom wall with edgewise positioned spacers positioned between each of said top and bottom walls and the top and bottom side, respectively, of a fragile article packed in said 55 carton, spaced double wall constructions forming abutment cushioning means for the front and rear of said article to serve as the front and rear sides of the carton, end panels each having an interior cushioning member for opposite ends of said article for completely cushioning and resiliently protecting said article to absorb impacts on any exterior part of the carton, said edgewise positioned spacer extending between the bottom wall and the article bottom comprising a plurality of looped structure, and fastening 60 means securing said looped structure together to provide a seat for said article.

12. A carton for cushioned shipping and displaying fragile articles of the character described 65 formed of a single blank of sheet material having score lines and through-cuts, said blank being folded on said score lines into interconnected sections 70 separate from each other by said through-cuts to provide a top and a bottom wall with edgewise positioned spacers positioned between each of said top and bottom walls and the top and bottom side, respectively, of a fragile article packed in said carton, spaced double wall constructions forming abutment cushioning means 75 for the front and rear of said article to serve as

the front and rear sides of the carton, and panels each having an interior cushioning member for opposite ends of said article for completely cushioning and resiliently protecting said article to absorb impacts on any exterior part of the carton, interlocking cross bracing portions foldably interconnected with said end panel sections extending between the double wall construction to form an abutment cushioning means at the rear of said article, said edgewise positioned spacer extending between the bottom wall and the article bottom comprising a plurality of looped structure, and fastening means securing said looped structure together to provide a seat for said article.

13. A carton for cushioned shipping and displaying fragile articles of the character described formed of a single blank of sheet material having score lines and through-cuts, said blank being folded on said score lines into interconnected sections separate from each other by said through-cuts to provide a top and a bottom wall with edgewise positioned spacers positioned between each of said top and bottom walls and the top and bottom side, respectively, of a fragile article packed in said carton, spaced double wall constructions forming abutment cushioning means for the front and rear of said article to serve as the front and rear sides of the carton, end panels each having an interior cushioning member for opposite ends of said article for completely cush-

ioning and resiliently protecting said article to absorb impacts on any exterior part of the carton, interlocking cross bracing portions foldably interconnected with said end panel sections extending between the double wall construction to form an abutment cushioning means at the rear of said article, said edgewise positioned spacer extending between the bottom wall and the article bottom comprising a plurality of looped structure, and fastening means securing said looped structure together to provide a seat for said article, said spaced double wall constructions forming the abutment means for the front and rear of said article and the top wall being foldably interconnected to permit positioning thereof to fully expose the front and top of said article for display purposes.

IRVING I. KLONER.
